CLAIM

The ornamental design for table foldably attachable to cooler, as shown and described.

DESCRIPTION

FIG. 1 is a rear perspective view of a table foldably attachable to a cooler, showing my new design;

FIG. 2 is a front perspective view thereof;

FIG. 3 is a top plan view thereof;

FIG. 4 is a rear elevational plan view thereof;

FIG. 5 is a bottom plan view thereof; and,

FIG. 6 is a side elevational view thereof.

The cooler is shown in phantom for illustrative purposes only and forms no part of the claimed design.
